STUD WRENCH

John Keiser, Windsor, Colo.

Application March 18, 1948, Serial No. 15,575

3 Claims. (Cl. 81—53)

1

This invention relates to a tool for removing and replacing threaded studs, and while more particularly designed for removing and replacing the cylinder head studs of automotive engines, it can be used wherever it is desired to obtain a rotating grip on a round rod or the like.

The principal object of the invention is to provide a stud wrench which will operate to firmly grip a variety of sizes of studs, and which can be employed to operate in either direction so that the stud may be either unscrewed from place or screwed into place.

Another object of the invention is to so construct the device that it will operate in a minimum of space, and so that it can operate with a variety of other wrenches, such as socket wrenches, monkey wrenches, bar wrenches, and the like.

A further object is to eliminate all screws, rivets, bolts, and nuts in a socket wrench construction, and to provide a wrench which can be readily assembled and dis-assembled.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side elevation of an embodiment of the improved wrench, illustrating it in place on a typical stud;

Fig. 2 is a longitudinal section therethrough, taken on the line 2—2, Fig. 3;

Fig. 3 is a top plan view thereof; and

Figs. 4, 5, and 6 are cross-sections, taken on the lines 4—4, 5—5 and 6—6, respectively of Fig. 2.

In the drawings a conventional threaded stud is indicated at 9.

The improved wrench employs a hollow, cylindrical, drum-like housing 10 having a central stud opening 11 in its bottom and an open top. The open top of the housing is surrounded on the interior by a ring groove 12.

Three dogs 13 are pivotally mounted on pivot pins 14 extending downwardly through pin openings in the bottom of the housing 10. Each dog extends to a relatively pointed edge 15 at its free extremity, and two sets of teeth 16 incline from the pointed edge 15 to form a toothed, spear-shaped head on the dog. The lengths of the dogs

are such that when swung to a radial position, the three pointed edges 15 will extend substantially to the axis of the housing 10.

The pivoted extremity of each dog is concentrically rounded about the axis of the pivot pin 14 and rests in a semi-cylindrical receiving socket 17 in the housing 10. The semi-cylindrical socket 17 forms the actual bearing for receiving the thrust of the dog.

10 A cam pin 18 extends upwardly from each dog into a rotatable cam plate 19 which rests upon the dogs 13. The cam plate has a central opening 20 for the passage of the stud 9 and three equally spaced, radially extending cam slots 21, there being one of the slots 21 for each of the pins 18.

It can be readily seen that if the cam plate is rotated back and forth, it will swing the dogs 13 back and forth about their pivot pins 14. The cam plate 19 is rotated by means of an operating arm 22, which, in the embodiment illustrated, is a slotted screw extending into a tapped opening in the cam plate 19. The arm 22 extends through a circumferential slot 23 in the housing. The slot is widened at its exterior to facilitate the insertion of the user's finger against the arm 22.

20 The housing 10 is rotated by means of a hollow shank 24 having a bottom flange 25 which rests against a shoulder 26 in the housing immediately above the cam plate 19. The flange is held in place by means of a spring ring 27 which expands outwardly into the ring groove 12. Three locking tongues 32 project from the circumference of the flange 25 into receiving notches 33 indented into the upper edge of the housing 10. The tongues act as keys to prevent relative rotation between the housing 10 and the shank 24.

25 The shank 24 may be provided with any type of wrench-receiving head. As illustrated, it is provided with hexagon wrench faces 28 on the exterior and a square socket 29 for receiving a socket wrench bar on the interior. It is also provided with diametrically extending bar openings 30 for receiving a turning bar 31.

30 Let us assume that it is desired to screw the stud 9 into place. The improved wrench is placed over the stud, as shown in Figs. 1 and 4, the latter extending upwardly through the openings 11 and 20 into the hollow interior of the shank 24. The operating arm 22 is swung clockwise in Fig. 3. This swings one face, which will be designated the left face, of each of the dogs 13 against the stud, as shown in Fig. 4. The entire wrench is then rotated clockwise, as indicated by the arrow in Fig. 4 to screw the stud 9 into place.

To unscrew the stud 9, the wrench is removed therefrom and the operating arm 22 is swung to the broken line position in Fig. 3. This swings the studs clockwise about their pivots so as to place them on the opposite sides of the stud as indicated in Fig. 6. This brings the opposite or "right" toothed face 16 of each dog into contact with the stud. The entire wrench is then rotated in a counter-clockwise direction as indicated by the arrow in Fig. 6, to unscrew the stud 9.

The force exerted to rotate the housing reacts against the dogs to create an end thrust thereon. This end thrust is absorbed by the contact of the rounded ends of the dogs against the bottoms of the receiving sockets 17 without strain on the pivot pins 14.

While a specific form of the improvement has been described and illustrated herein, it is desired to be understood that the same may be varied, within the scope of the appended claims, without departing from the spirit of the invention.

Having thus described the invention what is claimed and desired secured by Letters Patent is:

1. A wrench for rotating threaded studs comprising: a hollow, cup-like housing having a concentric stud opening in its bottom and an open top; a plurality of elongated dogs pivotally mounted at one end on said bottom at equally spaced intervals; a pointed, spear-shaped free extremity on the opposite end of each dog; teeth formed in the opposite sides of each spear-shaped extremity; a cam plate rotatably mounted in said housing over said dogs; a pin projecting upwardly from each of said dogs into a radially extending slot in said cam plate; means for rotating said cam plate from the exterior of said housing so as to swing said dogs about their pivots; a hollow shank; a flange formed on the lower extremity of said shank and fitting into the open top of said housing over said cam plate; means for locking said flange in said housing; means for preventing relative rotation between said flange and said housing; and wrench-engaging means on said shank.

2. A wrench for rotating threaded studs comprising: a hollow, cup-like housing having a con-

centric stud opening in its bottom and an open top; a plurality of elongated dogs pivotally mounted at one end on said bottom at equally spaced intervals; a pointed, spear-shaped free extremity on the opposite end of each dog; teeth formed in the opposite sides of each spear-shaped extremity; a cam plate rotatably mounted in said housing over said dogs; a pin projecting upwardly from each of said dogs into a radially extending slot in said cam plate; means for rotating said cam plate from the exterior of said housing so as to swing said dogs about their pivots; a hollow shank; a flange formed on the lower extremity of said shank and fitting into the open top of said housing over said cam plate; means for locking said flange in said housing; and keys projecting radially outward on said flange into receiving notches in said housing to transmit the rotation of said shank to said housing.

3. A wrench for rotating threaded studs comprising: a hollow, cup-like housing having a concentric stud opening in its bottom and an open top; a plurality of elongated dogs pivotally mounted at one end on said bottom at equally spaced intervals; a pointed, spear-shaped free extremity on the opposite end of each dog; a cam plate rotatably mounted in said housing over said dogs; a pin projecting upwardly from each of said dogs into a radially extending slot in said cam plate; and an operating member extending radially from said cam plate through a circumferential slot in said housing, by means of which said cam plate may be rotated to swing said dogs.
